UNITED STATES PATENT OFFICE.

HARRY U. KISTNER, OF SELIN'S GROVE, PENNSYLVANIA.

SAW-SET.

SPECIFICATION forming part of Letters Patent No. 640,471, dated January 2, 1900.

Application filed February 25, 1899. Serial No. 706,790. (No model.)

To all whom it may concern:

Be it known that I, HARRY U. KISTNER, a citizen of the United States, residing at Selin's Grove, in the county of Snyder, State of Pennsylvania, have invented a new and useful Improvement in Saw-Sets, which improvement is fully set forth in the following specification and the accompanying drawings.

My invention consists of a novel construction of saw-set by means of which several teeth of a saw-blade can be mechanically and accurately set at one time, provision being made for gripping and holding the saw firmly during the act of setting and for operating the setting and gripping devices practically simultaneously and by a common operating lever or handle.

It further consists of a novel construction for locking the gripping devices during the setting operation and for automatically releasing the same and for the adjustment of certain parts for accommodating saw-blades of different thickness or having different-sized teeth.

The invention further consists of novel details of construction, as will be hereinafter set forth.

Figure 1 represents a view, partly in side elevation and partly in section, on the line xx of Fig. 3 of a saw-set embodying my invention and in readiness to be applied to a saw. Fig. 2 represents a side elevation. Fig. 3 represents a top plan. Fig. 4 represents a fragmentary vertical section on line yy , Figs. 3 and 5. Fig. 5 represents an end elevation of the parts shown in Fig. 4. Fig. 6 represents a top plan of the parts shown in Fig. 4. Fig. 7 represents an end elevation of the setting-punches.

Similar letters and numerals of reference indicate corresponding parts in the figures.

Referring to the drawings, A designates a saw-set, the same consisting of a body B, having a handle C, by which the device is manipulated in connection with the lever D. The said body B is bifurcated or provided with the side blades 10, between which the lever D is pivoted at the point 11. The body B is provided with a stationary gripping-jaw 12 and movable gripping-jaw 13. The saw-blade is held between these jaws while the teeth are being set, and the upper ends are

beveled to form anvils, against which the teeth are pressed by the punches. The stationary jaw 12 is adjustable to accommodate saw-blades of different thickness, so that the teeth can be accurately set, and to secure this adjustability the face 14 of the jaw consists of an upright plate carried by shank 15, suitably guided by a rib or groove on the bottom of the body B. The shank is secured in its adjusted position by the thumb-screw 16, and to secure a fine adjustment a set-screw 17 is set in the body in the rear of the shank and presses against the rear end thereof. The movable jaw 13 is carried by a shank 18 between side plates or bifurcated portion of the body and held in place by a pin 19, secured to said side plates or the bifurcated portion, and passes through a slot 20 in said shank 18. The outer end of the shank 18 is pivoted to the lower end of a lever 21, the same being fulcrumed between the ears 22 upon the body. The upper end of the lever 21 is connected with the lever or knuckle 23 by means of a link 24. The said lever or knuckle 23 is situated at the upper rear portions of the body and between the side plates 10, and the connection between the link 24 and the lever 21 embraces a lost motion, being attained by a slot in said link. A spring 25 bears against a pin 26 upon the link 24 and against the side of the lever 21 and normally holds the parts in position, as shown in Figs. 1 and 2, although said spring makes the device adjustable automatically to accommodate saw-blades of different thickness and also to effect the locking of the gripping devices. The upper end 27 of the lever D is situated within the crotch of the lever or knuckle 23 and serves to throw the gripping devices in operative position when the lever D is turned on its fulcrum. The spring 28 holds the handle D normally in position, as shown in Figs. 1 and 2, and after the device has been operated this spring 95 serves to retract the punches and also to unlock the gripping devices, as fully described hereinafter, while the screw 29 regulates the closing of the handle or lever D.

The setting-punches 30 and 31 are retained by suitable guides 32 and 33 and move toward the anvils or beveled portions on the upper ends of the jaws 12 and 13. The rear punch 30 is pivotally connected with the arm 27 of

the lever D, while the punch 31 is pivoted upon the end of a link 34, that is pivoted to the lever D on the other side of its fulcrum. The pivotal connection between the punch 31 and link 34 conveniently comprises an upright collar 35 on the end of the arm within which a pin 36 on the punch 31 is swiveled. This pivot connection permits the lateral adjustment of the forward setting-punch 31 to vary the distances between the punches, so as to operate upon different-sized teeth. The punch 31 rests upon and is carried by a frame comprising two fingers 37, movable in guide-openings in the side plates of the body and connected together at one end by the plate 38. The fingers 37 are notched, as shown at 39, to receive the punch 31, it being noted that the guide 33 holds the punch in place therein. The frame and punch are moved laterally by means of a set-screw 40, swiveled to the plate 38 and having a threaded engagement with the body D.

As shown in Figs. 2 and 3, the side of the device is provided with a gage 41, consisting of a plate having one end secured to the body B by a screw 42 or otherwise, while its other end is free and overlaps the upper ends or anvils of the jaws. The rear end of said plate 41 is slotted, as shown at 43, to permit its free end to be swung over and away from the upper ends of the jaws, it being noted that said plate is further secured by a set-screw 43^x, having the screw connection with a side plate of a body and a swivel connection with the plate 41, whereby the latter can be moved laterally relative to the body.

Upon the rear end of the shank 15 is a jaw or face 44, situated opposite the jaw or face 45 of the body, and at the upper end of said jaws or faces 44 and 45 is a socket 46, in which a file can be reciprocated, it being understood that the set-screw 17 is withdrawn from the opening between the jaws 44 and 45 when this part of the device is in use. To limit the throw of the knuckle, its rear finger is provided with laterally-extending stops or projections 47, that engage the side plates 10 of the body when the gripping-jaws are locked.

The operation is as follows: The forward punch 31 is first adjusted laterally, according to the size of the teeth of the saw-blade, while the gage-plate 41 is also adjusted laterally, so that when it engages a tooth of the saw-blade the punches 30 and 31 are situated opposite the teeth to be set. The jaw 12 is then adjusted, if necessary, relative to the throw of the punches, so that the teeth will be accurately set on opposite sides of the saw-blade. The parts are then in position. (Best seen in Figs. 1, 2, and 4.) The saw-blade 48 is inserted, as shown, and when the handle C and the lever D are brought together the arm 27 of the latter engages one finger of the knuckle 23 and moves the gripping-jaw 13 into contact with the saw-blade. Owing to the relative arrangement of the pivotal connection between the arms 30 and 34 with the lever D

and the arrangement of the knuckle 23 the gripping-jaw 13 is moved into operative position before the punches 30 and 31 are moved to an appreciable extent. The knuckle 23 and connected parts are thereby moved to positions shown in dotted lines in Fig. 1 and locked in this position, since the pivot between the link 24 and the knuckle 23 is thrown to the opposite side of a line extending between the fulcrum with the knuckle and the pivot between the link and the lever 21. The yielding connection between the link and the lever 21 and the spring 25 permits such throw and the consequent locking of the gripping mechanism, as is evident. The gripping mechanism is thus locked and the lever D moves farther to reciprocate the punches 30 and 31, which engage the teeth of the saw-blade, setting them accurately and at a correct angle, as understood. When the lever D is released, the spring 28 throws it to its normal position to retract the punches 30 and 31 and also to unlock the gripping-jaws 12 and 13 by reason of the contact of the upper end of the arm 27 of said lever D with the other finger of the knuckle, the parts then assuming the position as shown in full lines in Figs. 1 and 2. The set-screw 29 obviously limits the movement of the lever D.

When the device is used as a saw-jointer, the set-screw 17 is retracted to permit the insertion of the saw-blade, while a suitable file can be manipulated within the socket or slot 46.

Having thus described my invention, what I claim as new, and desire to secure by Letters Patent, is—

1. In a saw-set, a body, the gripping-jaws and reciprocatory punches mounted thereon, a common lever for varying the distance between said jaws and for operating said punches, said punches and lever reciprocating in parallel paths, and connections between said punches and lever, said connections being secured to the lever on opposite sides of its fulcrum.

2. In a saw-set, a body, the gripping-jaws and reciprocatory punches mounted thereon, and means for varying the distance between said jaws, for locking and unlocking the same when in operative position, and for operating said punches.

3. In a saw-set, a body, the gripping-jaws and reciprocatory punches mounted thereon, and a common lever for varying the distance between said jaws, for locking and unlocking the same when in operative position, and for operating said punches.

4. In a saw-set, a body, the gripping-jaws and reciprocatory punches, and means for simultaneously decreasing the distance between said jaws, locking the same and advancing the punches, and for retracting the punches and unlocking said jaws.

5. In a saw-set, a body, the gripping-jaws and reciprocatory punches mounted thereon, and a common lever for simultaneously de-

creasing the distance between said jaws, locking the same and advancing the punches, and for retracting the punches and unlocking said jaws.

5 6. In a saw-set, a body, reciprocatory punches, a movable gripping-jaw connected with a lever or knuckle, and a lever connected with said punches and engaging said knuckle.

10 7. In a saw-set, a body, reciprocatory punches, a movable gripping-jaw yieldingly connected with a lever or knuckle, and a lever connected with said punches and engaging said knuckle.

15 8. In a saw-set, a body, reciprocatory punches, a movable gripping-jaw connected with a lever or knuckle, the connection between said jaw and lever or knuckle embracing spring-pressed yielding parts, and a lever connected with said punches and engaging 20 said lever or knuckle.

25 9. In a saw-set, a body, reciprocatory punches, a movable gripping-jaw carried by an upright lever 21, a knuckle or lever 23 mounted upon the body and connected with 30 said upright lever 21, and a lever connected with said punches and engaging said lever or knuckle 23.

35 10. In a saw-set, a body, reciprocatory punches, a movable gripping-jaw carried by an upright lever 21, a knuckle or lever 23 mounted upon a body and connected with said lever 21 by a link having a yielding spring-pressed connection with said lever 21, and a lever connected with said punches and 40 engaging said lever or knuckle 23.

11. In a saw-set, a body, gripping-jaws, reciprocatory punches, a laterally-adjustable frame having fingers upon which said punches are carried, guides for holding said punches in

place, and means for varying the distance between said jaws and operating said punches. 40

12. In a saw-set, a body, gripping-jaws, reciprocatory punches, a laterally-adjustable frame having notched fingers, one of said punches being situated within said notches, 45 guides situated above said punches and holding the same in position, and means for varying the distance between said jaws and for operating said punches.

13. In a saw-set, a body having gripping-jaws and reciprocatory punches, a laterally-adjustable gage situated at the side of the body and overlapping the space between the gripping-jaws to engage the teeth of a saw-blade, said gage being also adjustable to one 55 side of said space between the gripping-jaws.

14. In a saw-set, an adjustable, normally-stationary gripping-jaw, an automatically-adjustable movable gripping-jaw, means for moving the latter, and reciprocatory punches. 60

15. In a saw-set, an adjustable, normally-stationary gripping-jaw, an automatically-adjustable movable gripping-jaw, means for moving the latter embracing a yielding connection, and reciprocatory punches. 65

16. In a saw-set, a body, reciprocatory punches, a movable gripping-jaw, a knuckle, a connection between said knuckle and movable gripping-jaw, a toggle-joint in said connection, said knuckle forming one member of 70 said toggle-joint, and a lever engaging said knuckle, said lever serving as means for operating said punches.
